TOY AIRPLANE

Gustav Boehme, Ludenscheid, Germany

Application June 24, 1935, Serial No. 28,203
In Germany February 23, 1933

16 Claims. (Cl. 46—76)

This invention relates to instructive toy airplanes, and has for its object to provide a flying toy airplane suited particularly for purposes of instruction by being equipped with means which prevent smashes during landing. The life of the improved airplane is therefore quite long, and as the plane is further capable of withstanding rough handling, the player is enabled to carry out a large number of flights under the most varied conditions and circumstances for his instruction.

The invention, above all, aims at protecting the hollow wings during landing, which for this purpose are connected with the fuselage so that they can elastically fold upwards and return to their position. On striking the ground during landing of the airplane, the wings immediately recede upwards, the shock being absorbed by cushioning, and owing to this cushioning effect instantly return automatically to operating position, so that the airplane is practically ready for service again directly after landing. If the wings are braces, the support struts, according to their arrangement on the underside or top of the wing, are elastically extensible or elastically bendable, and in the latter case the support strut consists preferably of curved steel band which in simplest manner combines stiffness and elasticity.

The invention further provides to render the rear part of the body carrying the tail unit elastically bendable so as to permit the tail unit to incline considerably towards the side and return automatically in case of bumpy landings, whereby the landing forces effective at that point are also converted into cushioning action and smashes prevented. Furthermore, the forces stressing the wings are correspondingly reduced thereby.

A particularly advantageous construction results if the wing having a hollow profile can elastically bend transversely to the direction of flight, as the deflection will then take place directly at the striking points. An elastically bendable construction is attained by producing the longitudinal carrying elements of the wing structure, such as spars, nose and trailing edge stiffening strips, from transversely cambered steel band.

By way of example, the invention is illustrated in the accompanying drawings, in which Figure 1 is a partial top view of the toy airplane; Fig. 2, a side view thereof with the front wing removed; Figs. 3 to 8 are enlarged sections on the lines III—III, IV—IV, V—V, VI—VI, VII—VII, VIII—VIII, of Figs. 1 and 2; Fig. 9 is an enlarged

section of the spar connection; Fig. 10, a top view of another form the rear part of the body; Fig. 11, a section on the line XI—XI, of Fig. 10; Figs. 12 and 13 show the use of differently constructed support struts; Figs. 14 to 16 are views of an elastically bendable wing, Fig. 14 being a longitudinal section on the line XIV—XIV, of Fig. 15; Fig. 15 being a top view and Fig. 16 an enlarged section on the line XVI—XVI, of Fig. 15.

Referring to the drawings, 12 are warping structures of hollow wings shown without covering and consisting each of a U-shaped light metal spar 41, the U-shaped light metal ribs 38 arranged thereon and secured thereto by tubular rivets, a hollow front strip 18 and an angular metal trailing edge stiffening strip 47. On each wing 30 designates a support strut of cambered steel band disposed on the upper side of the wing. The strut 30 is secured with one against rotation to an angular member 85 which reinforces the point of intersection of the longitudinal spar 41 and a rib 38, and the other end thereof extends into a member 50 secured to the body 15 and serving for adjusting the support struts and having a longitudinal slot 51 in which a screw 52 is adjustable and fixable. To increase the stiffness of the struts the upper end of the band 30 is connected with the member 50 by means of a filling 88 to maintain the camber.

The fuselage 15 contains in an opening in its lower part a thick fitting and carrying rubber piece 91 which as a filler directly connects both wing spars 41 by being arranged in the depression of the spars and united therewith by the clamping plate 92 and the screw 93, as indicated in Fig. 9. The second point of attachment of each wing is located at its trailing edge whose stiffening strip 47 extends into a steel band 94 that can be screwed to the body, as shown in Fig. 5. On each side of the body a projection 95 is further provided which forms a butt joint with the front edge 18 of the wing and serves for supporting it.

In case of oblique bumpy landings, the wing 12 touching the ground deviates upwardly owing to its jointlike connection to the body 15 by means of the elastic members 91, 94 and its support by the bendable steel band strut 30, so that the landing shock is converted into cushioning action and does not cause destruction of the wing. After the effect of the shock has been overcome the wing instantly returns automatically to its operating position.

As Fig. 12 indicates, instead of cambered steel

band, rigid strut members 53 may be used for instance on the upper side of the wing articulated to the body, which are interconnected by an elastic joint 54 and articulated to the body and wing. Support struts of this kind also bend and automatically extend again. According to Fig. 13, on the underside of the wing connected to the body 15 by the joint 55 elastically extensible struts, such as the telescopic tubes 56 cushioned 10 relative to one another, can be provided which are articulated to the body and wing and permit elastic upward deviation and automatic restoration of the latter.

The rear part of the body comprises two cambered steel bands 96 which face each other with their hollow sides, are connected in cambered fashion to the body 15 and the tail unit 13 by, say, the fillers 88 and spread at half of their length by an inserted distance piece 97. This spreading 20 renders the steel bands 96 which are covered with a yielding fabric 89 in streamline manner torsion proof.

In the construction according to Figs. 10 and 11 the two cambered steel bands 96 are connected 25 in spread position and cambered fashion to the end 15a of the body, so that a special spreading member can be dispensed with. The invention of the bendable rear part of the body is not limited to the embodiments shown, and the bands 96 may 30 also be arranged horizontally and face one another with their cambers.

The surfaces of the tail unit 13 consist of artificial resin material reinforced at the edge by the metal strips 98. Such surfaces are very light 35 and resistant. When the airplane lands obliquely or on its nose, the tail unit, owing to the bending of the steel band body 96, elastically deviates to the side and automatically returns into normal position after the deflection of the body is completed.

The parts 15, 18, 41, 47 may consist of suitable structural materials like metal, wood or artificial substances. For covering the wings canvas or other material can be used. The airplane can 45 be thrown into the air by hand or by a catapult device engaging the hook 57 or driven by a compressed air motor, etc. and propeller. By displacing the point 52 in the longitudinal slot 51 the wings are twisted or warped, whereby they are set 50 differently, so that the training flights can be made highly interesting.

In the construction according to Figs. 14 to 16 the wing 12a is connected to the body 15 by a screw 58 so as to be easily detachable. The ribs 55 38a are pressed from light metal or consist of some other strong material. The longitudinal carriers firmly connected with the ribs and forming part of the wing structure, such as the principal spar 41a, the nose strip 18a and the trailing edge 60 stiffening strip 19a, are formed from a cambered steel band whose concave curvature faces the ribs 38a and is accurately adapted to the rib profile at the points of connection. The steel bands 41a are the flanges of the main spar whose 65 web is formed by the ribs 38a. The steel bands are connected by means of solid or tubular rivets 45 on the outside of the rib flanges 39a. The nose strip 18a and the trailing edge stiffening strip 19a are provided singly and only on one side of the 70 ribs, which makes it possible for them to deflect to the same extent as the main spar whose widely spaced flanges touch one another during bending of the wing. 99 are bracings of wire, threads, etc. to render the wing more torsion proof. 100 is a 75 thread connecting the lower flanges of the nose of

the rib. The wing tip 101 may consist of light metal and is preferably connected only to the lower one of the steel bands forming the main spar. 30a designates the support strut of cambered steel band arranged on the upper side of the 5 wing and leading to body point 52a adjustable and fixable in the longitudinal slot 51a. The covering 59 of the wing structure indicated in Fig. 16 consists of elastic material like paper, fabric, etc.

The new wing whips locally to such an extent 10 that it can be wound up transversely to the direction of flight. In practical flying the wing is of course not exposed to this extraordinary stress which affects the riveted points, as the shocks due to landing will either be taken up by the wing 15 tip alone or bring about the bending of the support strut.

The wing according to the invention may, in certain cases, even be relied upon to have a stabilizing effect during flying. For example, if a 20 squall strikes a wing and bends the unsupported tip, it will result in a reduction of lift and disturbance of balance. By adjusting the strut 30a by means of the members 51a, 52a the wing 25 can be warped and set differently.

I claim:—

1. An airworthy toy airplane, comprising a body, hollow wings connected with the body in jointlike manner and struts of cambered steel band between the wings and body disposed on top, 30 the said steel bands being adapted to maintain the wings in their normal operating position during normal flight, but yielding to shocks coming from the underside of the wings, such as those resulting from oblique landings, to cause them to 35 fold upwards and to return automatically into their original operating position when the stresses are removed.

2. An airworthy instructive toy airplane, comprising a body and hollow wings with struts to 40 the body, the wings being connected with the body in jointlike manner and warping, the support struts consisting of cambered steel band, the points of connection of the steel band struts and body being adjustable and fixable in flying direc- 45 tion.

3. A toy airplane, comprising a body and hollow wings, the wings being supported relative to the body by elastically bendable struts and having each a spar, a front strip and a trailing edge 50 stiffening strip, said spars being interconnected by a flexible member and the trailing edge stiffening strips being connected with the body by steel band.

4. A toy airplane, comprising a body, a tail unit 55 on the rear part of the body and hollow wings, elastic connecting means between the body and wings for rendering the wings elastically foldable in upward direction and returnable to their normal position, the rear part of the body carrying the tail unit being elastically bendable, the rear part of the body carrying the tail unit being formed of spread cambered steel bands coming together in front and rear and the steel bands being provided at at least one point of their free 60 length with a firmly inserted distance piece for spreading them.

5. A toy airplane, comprising a body, a tail unit 70 on the rear part of the body and hollow wings, elastic connecting means between the body and wings for rendering the wings elastically foldable in upward direction and returnable to their normal position, the rear part of the body carrying the tail unit being elastically bendable, the rear part of the body carrying the tail unit 75

consisting of cambered steel bands connected with a broad end of the body and converging towards the tail unit.

6. An airworthy instructive toy airplane, comprising a body, a tail unit and hollow warping wings, said wings being connected with the body in jointlike manner and struttred relative to the body by cambered steel bands, the points of connection of the cambered steel band struts and body being adjustable and fixable in flying direction, the rear part of the body carrying the tail unit being elastically bendable.

7. A toy airplane, comprising hollow wings with a covering of soft material and an internal carrying structure, said structure having elastically yielding longitudinal carriers and ribs connected therewith, at least some of these longitudinal carriers consisting of cambered steel band for rendering the wings elastically bendable and automatically returnable to their extended position.

8. A toy airplane, comprising a hollow wing with a covering of soft material, a carrying structure inside the wing consisting of at least one longitudinal spar and cross ribs connected therewith, said longitudinal spar having flanges of cambered steel band and being elastically bendable.

9. A toy airplane with hollow wing, said wing having an internally disposed structure comprising at least one longitudinal spar, a nose strip and a trailing edge stiffening strip, the flanges of said spar and the nose and stiffening strips consisting of cambered steel band.

35 10. A toy airplane with hollow wing, said wing comprising an inner structure and a covering of soft material, the structure consisting of ribs and longitudinal carriers connected therewith, said carriers being made of cambered steel band and with their concave side disposed on the outside of the ribs.

11. A toy airplane, comprising a body, hollow wings and a strut arranged between the body and wings above the latter, the wings having an inner structure of ribs, longitudinal carriers connected with said ribs and a covering of flexible material, said longitudinal carriers and strut consisting of cambered steel band.

12. An airworthy toy airplane, comprising a body and hollow wings, the wings being jointlike connected with the body and braced against the latter by struts disposed on top, the said bracing struts resisting compressive stress resulting under flying conditions and made elastically flexible, said jointlike connection and elastic flexibility being adapted to permit the wings to swing upwards when encountering landing shocks or stresses from the under side of the

wing and to restore them automatically into their normal operating position when the stresses are removed.

13. A toy airplane of the kind described, comprising cambered steel bands forming elastically bendable elements thereof, said cambered elements being connected and incorporated into the structure with their camber maintained at the connecting points and forming elastic supporting and fastening members which permit automatic bending and yielding upon receiving landing shocks with automatic restoration after the shocks cease.

14. An airworthy toy airplane, comprising a body and hollow wings, the wings being jointlike connected with the body and braced against the latter by struts disposed on the under side of the wings, the said bracing struts resisting tensile forces resulting under flying condition and made elastically extensible, said jointlike connection and elastic extensibility being adapted to permit the wings to swing upwards when encountering landing shocks or stresses from the under side of the wing and to restore them automatically into their normal operating position when the stresses are removed.

15. An airworthy airplane, comprising a body, hollow wings with spaced upper and under surfaces, a bracing structure in said wings, the structures being jointlike connected with the body, elastic means adapted to co-operate with the jointlike connection and to maintain the wings in their normal operating position during normal flight, said jointlike connection and elastic means being adapted to permit the wings to assume limited upward yielding movements when encountering landing shocks or stresses from the under side of the wing and to restore them automatically into their normal operating position when the stresses are removed.

16. An airworthy toy airplane, comprising a body, hollow wings with spaced upper and under surfaces, a bracing structure in said wings, a rigid tail unit, elastic, structural supporting and connecting means between the body and the root of the wing structures and between the body and rigid tail unit, the said elastic supporting and connecting means being adapted, on the one hand, to maintain the wings and tail unit in their normal operating position with respect to the body during starting and flight and on the other hand cause them to assume limited yielding movements when encountering landing shocks and to restore them automatically into their normal operating position when the stresses are removed.

GUSTAV BOEHME.
